[57] CLAIM

The ornamental design for a computer mouse, as shown
and described.

DESCRIPTION

FIG. 1 is a top view;
FIG. 2 is a side view, the opposite side is a mirror image;
FIG. 3 is a front elevation view; and,
FIG. 4 is a rear elevation view.
The bottom plan view is plain and unornamented.
The broken line drawing of a cord is for illustrative
purposes only and forms no part in the claimed design.

FIG. 1

FIG. 2

FIG. 3

FIG. 4
